C. T. MASON,
IGNITION DYNAMO,
APPLICATION FILED MAY 1, 1916

1,318,219.

Patented Oct. 7, 1919.

Inventor

UNITED STATES PATENT OFFICE.

CHARLES THOMAS MASON, OF SUMTER, SOUTH CAROLINA, ASSIGNEE TO SPLITDORF ELECTRICAL COMPANY, OF NEWARK, NEW JERSEY, A CORPORATION OF NEW JERSEY.

IGNITION-DYNAMO.

1,318,219.

Specification of Letters Patent.

Patented Oct. 7, 1919.

Application filed May 1, 1916. Serial No. 94,698.

To all whom it may concern:

Be it known that I, CHARLES THOMAS MASON, a citizen of the United States, residing at Sumter, in the county of Sumter 5 and State of South Carolina, have invented certain new and useful Improvements in Ignition-DYNAMOS, of which the following is a specification, reference being had to the accompanying drawing.

10 This invention relates to ignition dynamos commonly termed magnetos and specifically to the manner of attaching the conducting cable and safety spark gap member to the generating coil thereof.

15 In my co-pending application, Serial No. 92,196, I have shown and described a magneto of a well known type, having a high tension terminal mounted on the side of the casing of the magneto, and the present 20 invention eliminates the expense of such a terminal and enables the spark plug cable to be connected directly to the winding, thereby eliminating all contacts in the circuit leading to the spark plug or other device.

25 In the accompanying drawing, Figure 1 is an end view of the magneto broken away to show the arrangement of the cable connection. Fig. 2 is a side view, with one of 30 the cover plates removed. Fig. 3, is a view of the coil unit. Like figures of reference denote the same parts wherever they are shown.

35 For the sake of illustration, I show the present invention used in connection with a machine as shown and described in my U. S. Patent #1,081,760, dated December 16, 1913. Certain other features illustrated in the appended drawings were disclosed and claimed in connection with my application executed 40 April 8, 1916, hereinbefore mentioned.

The numeral 1 indicates a suitable cover bent around the field magnet or magnets 2 and secured to the base 3 in any suitable manner, such as by the screws indicated at 45 4 and 5. This cover together with side plates 6 and 7 completely inclose the magneto, with the exception of the usual interrupter mechanism, which is inclosed by the cap 8 held in position by a suitable cover spring 50 9, supported on post 10. The two cover plates are bolted together by through bolts, indicated at 11 and 12, or in any suitable manner.

On the side plate 7 is mounted an insulat-

ing bushing 13, held thereon in any suitable manner, and passing through this bushing is the spark plug cable 14, the inner end 15 of which may be beveled as shown in Fig. 3, so that the bare end of the conductor 16 projecting therefrom may be 60 grasped by the over-lapped end 17 of the spark gap member 18.

The cable and spark gap member being laid across the top of the winding 19, the outer end 20 of said winding is brought 65 through the insulating wrapper thereabout, and soldered or otherwise connected to the member 18. The cable is then lashed to the winding by means of a suitable layer of tape indicated at 21. It will be noted that 70 the spark gap member 18 forms with the core 22, a safety gap for limiting the potential of the current generated by the winding.

75 It will be seen from the foregoing description that the removal of the side plate cover does not break the electrical connection between the spark plug cable and the winding; that there are no brushes or other movable contacts in the circuit between said 80 winding and the spark plug; and that the coil Fig. 3, forms a generating unit, which may be removed and replaced without breaking any of the high tension electrical connections.

85 Having thus described my invention, I claim:

1. In an ignition dynamo, a unit generating coil having a core, a winding about said core, a conducting cable connected to 90 said winding, a member forming a safety spark gap point connected to said cable, and means comprising a cover about said winding whereby said cable and member are secured thereto, substantially as described. 95

2. In an ignition dynamo, a unit coil structure comprising a core, a generating winding about said core, insulation about said winding, a contact member over-lying a portion of said winding and adapted to 100 form a safety spark gap with said core, means connecting said member to said winding, a conductor clamped to said member and connected with said winding, and means for securing said member and conductor to 105 said winding, substantially as described.

3. In an ignition dynamo, a frame-work, a casing including side plates inclosing said

framework, a generating winding supported within said casing, a conducting cable connected to said winding and extending outwardly through one of said plates, and means supporting said winding in said framework whereby it may be removed therefrom as a unit, together with said attached cable, substantially as described.

4. In an ignition dynamo, a framework, 10 a casing including side plates inclosing said framework, a stationary core having a high tension generating winding thereon located

within said casing, a high tension conducting cable connected directly to said winding, means including a cover about said 15 winding for mechanically securing said cable thereto and means supporting said core and winding in said framework whereby they may be removed as a unit, together with said attached cable.

In testimony whereof I hereunto affix my signature.

CHARLES THOMAS MASON.
